UNITED STATES PATENT OFFICE

OSCAR H. FAIRCHILD, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS FOR HYDROCARBON OIL CONVERSION

Application filed January 14, 1926. Serial No. 81,156.

This invention relates to improvements in the process and apparatus for hydrocarbon oil conversion, and refers more particularly to the production of lighter gravity hydrocarbon products from heavy gravity hydrocarbons by subjecting the hydrocarbon oil to vapor phase cracking.

In the present vapor phase cracking processes now in use, one of the objections existing is that it is impossible to transmit the most efficient high heat to the vapors due primarily to the loss of heat units in passing through the metal container wall and the rapidity with which such metal container wall burns out. Attempts have been made to utilize refractory walls, but the same objection of inefficient heat transmittal through the refractory walls exists.

The present invention is primarily directed to the idea of subjecting the hydrocarbon oil to cracking in the vapor phase by subjecting the vaporous products to the direct physical contact of highly heated gases.

Briefly, the invention in one specific embodiment comprises introducing the hydrocarbons, either in liquid form or vapor form, or in both liquid and vapor form, into the highly heated zone of a heat generator at a point immediately adjacent the fuel gasification zone, that is, the zone where the fuel, such as coke, for example, is gasified in the heat generating process. A bed of coke or similar carbonaceous fuel is maintained above the point at which the hydrocarbons are introduced. The hydrocarbons are thus subjected to direct contact with the heated gases generated, and the vapors and gases mingle in the bed of carbonaceous fuel at a prolonged high temperature.

The introduction of the hydrocarbon material directly into the zone of highest heat allows a wide variation in temperatures to which the vapors may be subjected during the cracking reaction. By regulating the agent introduced to accelerate or retard heat generation, it is possible to simultaneously control the temperature and regulate the percentage of saturants and unsaturants in the final product produced.

Many other advantages and objects will be

more particularly brought out in the following description.

In the drawing, the single figure is a diagrammatic side elevational view, partly in vertical section, of the apparatus.

Referring more in detail to the drawing, 1 designates a vertical drum or chamber internally insulated with suitable refractory material as shown at 2. The upper end of the vertical chamber 1 may be closed by the top closure plate 3, on which is mounted a dome 4 having a movable door 5 through which charges of coke or similar carbonaceous material may be introduced to the chamber. On one side of the dome 4 is a supporting bracket 6 in which is pivotally mounted an arm 7 having a movable weight 8. This arm 7 has pivotal engagement with a downwardly extending link 9 on which is mounted a valve 10, closed from the inside. Intermediate its length, the chamber 1 may be provided with any suitable number of peek holes or poke holes 11. They may be stationed at any height and in any number which may be desired. Also intermediate the height of the chamber 1, it tapers inwardly along the line 12 to provide a constricted portion 13, which constricted portion serves as a constricted orifice for the purpose of bringing the hydrocarbon vapors and hot gases into intimate admixture. Below the constricted portion 13, the drum tapers outwardly again along the line 14 until the tube reaches the diameter of the tube above, shown at 15. The portion of the drum 15 below the constricted portion 13 constitutes the heat generating zone, and there is mounted therein a grate 16, which may be of any construction, and which is shown diagrammatically. In some cases, the grate 16 may be omitted.

The drum is mounted on a base 17 and is provided with the ash pit 18 below the grate 16, where the latter is used, said ash pit 18 being cleaned through the door 19. Air under sufficient pressure to penetrate the entire mass may be introduced through the inlet 20, controlled by the valve 21. In addition to air, an endothermic agent such as steam, carbon dioxide, or other agent may be introduced simultaneously with the air through the same

inlet pipe 21, the proportion of air to endothermic agent being regulated in an obvious manner at a point not shown on the drawing.

A bed of refractory material 22, which may be crushed firebrick or other refractory material, is maintained on the grate 16 for the purpose of protecting the grate from the intense heat generated in the chamber 15. Where it is not necessary to use the grate, for instance where utilizing the usual domestic or metallurgical coke, the grate 16 may be dispensed with as well as the bed of refractory material 22.

I have shown the heat generating chamber 15 as an integral part of the chamber 1. It is to be understood, of course, that the heat generating chamber 15 may be a separate unit, it being desired only to bring a highly heated gas into direct contact with the hydrocarbons in the presence of a carbonaceous material, such as coke. The coke or other carbonaceous material 23 may be maintained in a substantial body within the chamber 1.

As one of the features of the present invention, a header 24 is positioned adjacent the constricted portion 13 and is provided with a plurality of discharges 25. The header 24 receives the hydrocarbons, which may be in liquid form, or in liquid and vapor form, from any suitable source of supply, such, for instance, as from storage or from a concurrently operated distilling or cracking process. The object of providing a number of discharge pipes 25 is to uniformly distribute the introduced hydrocarbon material in order that there may be a maximum efficiency of contact between said hydrocarbons and said hot gases. I have shown the discharge pipes 25 as discharging at a point below the constricted portion 13. It is obvious, of course, that I may introduce said hydrocarbons directly into the constricted zone. Immediately upon being introduced into the drum, the hydrocarbons, whether in vapor or liquid form, will be subjected to physical contact with the highly heated gases generated as before described, and by means of the constricted portion 13, a thorough intermingling and effusing will take place. This highly heated mixture will pass upwardly through the body of carbonaceous material 23, eventually causing said body to be maintained in a highly heated state.

The vapors and gases passing out through the vapor gas pipe 26, controlled by valve 27, pass to any suitable form of scrubber or condenser 28, the condensate being withdrawn through the line 29, controlled by valve 30. Two chambers 28 and 31 are shown, but their use is optional. The vapors passing through the pipe 26 may be subjected to any form of treatment, such as dephlegmation, condensation, absorption, or the like.

The carbon particles precipitated in the upper section 32 of the chamber 1 will be-

come a part of the carbonaceous fuel 23, and the non-combustible part thereof will eventually be withdrawn as ash.

The process may be operated either continuously or as a batch operation.

The introduction of the hydrocarbons through the branches 25 into the heated zone 15 permits of wide variations in the range of temperature to which the vapors may be subjected during cracking reaction, for instance, between, say, 1000° F. to 2400° F. more or less. These temperatures are merely illustrative, and higher temperatures may be attained as follows: with the employment of pre-heated dry air, the temperature may reach 2400° F. plus the temperature of the pre-heated air; using cold dry air, the temperature may reach approximately 2400° F. more or less; if an endothermic agent, such as steam or carbon dioxide gas, is used simultaneously with the air, the temperature may range between 2400° F. more or less as a maximum, and 1200° F. more or less as a minimum. In any case, the temperature chosen as proper for a given effect can be controlled within close limits in actual operation.

By controlling the amount of air and other agent introduced through the line 20, it is possible to control the percentage of fixed, permanent gas and condensable vapors.

In using steam with the air blast, free hydrogen will be liberated and become an important fraction of the vapor and gas mixture.

A practical source of carbon dioxide gas for use as an endothermic agent may be any flue gas. This will be desirable when the presence of hydrogen in large volumes, such as would be the case when using steam, is objectionable in the upper chamber 32. It may be pointed out that this chamber 32 is, in effect, a reaction chamber.

From the foregoing, it will be observed that I may provide a source of heat within the reaction zone, the hydrocarbons being brought into direct contact with the hot gases which bring about the desired reaction. I also provide a constricted zone to cause an efficient intermingling of the hot gases and hydrocarbon. There is also provided a reaction zone which allows the gases and vapors a maximum time to react while simultaneously holding the vapors at an elevated temperature in the presence of the highly heated carbonaceous body 23.

As another feature of the invention, in case it is desired to use a catalyst, it may be introduced into the carbonaceous body 23. The temperatures used may be very accurately controlled, and the chemical composition of the generated gas may be controlled by regulating the volume of free hydrogen produced.

I claim as my invention:

A vapor phase cracking process for con-

verting heavy hydrocarbon oils into lower boiling products which comprises maintaining combustion at the lower portion of a vertical column of solid carbonaceous material and passing the resultant hot gases upwardly through said column, restricting the path of said hot gases to form a region of increased velocity above the zone of combustion, introducing the heavy oil to be cracked in vapor form adjacent said region of increased velocity and at a substantial distance below the top of said column, causing the oil vapors to pass upwardly through said column in intimate admixture with said hot gases whereby the oil is cracked in the vapor phase and the resultant carbon deposited in said carbonaceous material, so controlling the cracking conditions in said column that complete gasification of the oil is prevented and substantial amounts of condensable lighter hydrocarbons are formed therein, removing said gases and the vapors of said condensable lighter hydrocarbons from the upper portion of said column, and condensing said vapors as the final product of the process.

OSCAR H. FAIRCHILD.
